US00D740041S

(12) **United States Design Patent**
Chadwick et al.

(10) **Patent No.:** **US D740,041 S**
(45) **Date of Patent:** **** Oct. 6, 2015**

(54) **STOOL**

- (71) Applicant: **Humanscale Corporation**, New York, NY (US)
- (72) Inventors: **Donald Chadwick**, Los Angeles, CA (US); **Jeffrey Koffman**, Santa Monica, CA (US); **Todd Brunner**, Brooklyn, NY (US); **Gregory Allison**, Allentown, PA (US)
- (73) Assignee: **Humanscale Corporation**, New York, NY (US)
- (**) Term: **14 Years**
- (21) Appl. No.: **29/498,012**
- (22) Filed: **Jul. 30, 2014**

OTHER PUBLICATIONS

Non-Final Rejection mailed Dec. 11, 2009 in the U.S. Appl. No. 12/131,335, filed Jun. 2, 2008, "Active Dynamic Seating Device".

Primary Examiner — Susan Bennett Hattan*Assistant Examiner* — Vy Koenig(74) *Attorney, Agent, or Firm* — Kelley Drye & Warren LLP**(57) CLAIM**

We claim the ornamental design for a stool, as shown and described.

DESCRIPTION

FIG. 1 is a front, rear, left, and right side view of a stool embodying the present invention;

FIG. 2 is a top view of the stool of FIG. 1; and,

FIG. 3 is a bottom view of the stool of FIG. 1.

The broken lines shown in the drawings depict portions of the stool that form no part of the claimed design.
